(57) CLAIM

The ornamental design for shorts as shown and described.

DESCRIPTION

FIG. 1 is a front view of shorts showing our new design; FIG. 2 is a right side front perspective view thereof; and, FIG. 3 is a left side front perspective view thereof.

The broken lines immediately adjacent to and surrounding the two photographic areas define the peripheral bounds of the claimed design and form no part thereof. The broken lines depicting the remainder of the shorts form no part of the claimed design.
